(57) **CLAIM**

The ornamental design for a hair styling tool, as shown and described.

DESCRIPTION

FIG. 1 is a perspective view showing our new design; FIG. 2 is a front elevational view, the rear elevational view is a mirror image;

FIG. 3 is a left side elevational view;

FIG. 4 is a right side elevational view;

FIG. 5 is a top plan view;

FIG. 6 is a bottom plan view;

FIG. 7 is a perspective view of an alternate embodiment showing our new design;

FIG. 8 is a front elevational view of FIG. 7, the rear elevational view is a mirror image;

FIG. 9 is a left side elevational view of FIG. 7;

FIG. 10 is right side elevational view of FIG. 7;

FIG. 11 is a top plan view of FIG. 7; and,

FIG. 12 is a bottom view of FIG. 7.

The portions of the Figures shown in phantom lines are not part of the claimed design but are for illustration only.
